(57) **CLAIM**

The ornamental design for a light bar assembly, as shown and described.

DESCRIPTION

FIG. 1 is a top perspective view of a light bar assembly, in accordance with the present invention;

FIG. 2 is a bottom right hand perspective view of a light bar assembly, in accordance with the present invention;

FIG. 3 is a top plan view of the light bar assembly of FIG. 1, in accordance with the present invention;

FIG. 4 is a left side elevation view of the light bar assembly of FIG. 1, in accordance with the present invention;

FIG. 5 is a right side elevation view of the light bar assembly of FIG. 1, in accordance with the present invention;

FIG. 6 is a bottom plan view of the light bar assembly of FIG. 1, in accordance with the present invention;

FIG. 7 is a rear elevation view of the light bar assembly of FIG. 1, in accordance with the present invention; and,

FIG. 8 is a front elevation view of the light bar assembly of FIG. 1, in accordance with the present invention.

The broken lines in the figures showing attachment portions on the light bar assembly for attaching to a vehicle are for illustrative purposes only and forms no part of the claimed ornamental design.
